US00D469830S

(12) **United States Design Patent** (10) Patent No.: **US D469,830 S**
Manville (45) Date of Patent: ** **Feb. 4, 2003**

- (54) **CRAFT KIT CONSTRUCTION
COMPONENT—CAP WITH FACIAL
FEATURES**
- (75) Inventor: **Richard B. Manville**, Los Angeles, CA (US)
- (73) Assignee: **Mattel, Inc.**, El Segundo, CA (US)
- (**) Term: **14 Years**
- (21) Appl. No.: **29/157,918**
- (22) Filed: **Mar. 26, 2002**
- (51) LOC (7) Cl. **21-01**
- (52) U.S. Cl. **D21/658; D21/659**
- (58) Field of Search **D21/658, 659, D21/660, 661, 577, 621–649, 594, 593, 484, 487, 488, 490, 493, 498, 503, 502; D2/865, 866, 869, 870, 872, 873, 882; 446/268, 337, 341, 321, 391, 392, 394, 372, 97–101, 387; D11/160, 164; 2/173, 195.1, 209.13, 423**
